Primary Examiner — Michelle E. Wilson*Assistant Examiner* — Celse Moore, Jr.(74) *Attorney, Agent, or Firm* — Matthew G. McKinney; Allen, Dyer et al.(57) **CLAIM**

The ornamental design for a golf cart floor mat, as shown and described.

DESCRIPTION

FIG. 1 is a top view of a golf cart floor mat; FIG. 2 is a bottom view of a golf cart floor mat thereof; FIG. 3 is a left side view of the golf cart floor mat thereof; FIG. 4 is a right side view of the golf cart floor mat thereof; FIG. 5 is a front view of the golf cart floor mat thereof; FIG. 6 is a rear view of the golf cart floor mat thereof; FIG. 7 is a top view of a golf cart floor mat according to a second embodiment of my new design; FIG. 8 is a bottom view of a golf cart floor mat thereof; FIG. 9 is a left side view of the golf cart floor mat thereof; FIG. 10 is a right side view of the golf cart floor mat thereof; FIG. 11 is a front view of the golf cart floor mat thereof; and, FIG. 12 is a rear view of the golf cart floor mat thereof. The broken lines along the outer edge of the golf cart floor mat in FIGS. 1 and 7 depict the bounds of the claim and form no part thereof. The broken lines in FIGS. 2-6 and 8-12 depict portions of the golf cart floor mat that form no part of the claimed design. Portions of the golf cart floor mat in FIGS. 7-12 have been cross hatched to indicate color.
